CLAIM

The ornamental design for a lid and handle for a water pitcher, as shown and described.

DESCRIPTION

FIG. 1 is a left rear perspective view of a lid and handle for a water pitcher showing the new design;

FIG. 2 is left front perspective view thereof;

FIG. 3 is a right side view thereof;

FIG. 4 is a left side view thereof;

FIG. 5 is a front view thereof;

FIG. 6 is a rear view thereof;

FIG. 7 is bottom view thereof; and,

FIG. 8 is a top view thereof.

The broken line showing environmental structure is for illustrative purposes only and forms no part of the claimed design.
